DESIGN FOR A LAWN UMBRELLA

Elizabeth Harrison Hanna, Montclair, N. J.

Application July 16, 1936, Serial No. 63,877

Term of patent 14 years

To all whom it may concern:

Be it known that I, Elizabeth Harrison Hanna, a citizen of the United States, residing at Montclair, in the county of Essex and State of New Jersey, have invented a new, original, and ornamental Design for Lawn Umbrellas, of which the following is a specification, reference being had to the accompanying drawing, forming part thereof.

It will be understood that the upper portion shown in outline in Figure 2 will have the appearance of the lower portion shown in full lines. The design is in bright colors to simulate generally a poppy in form and coloring.

I claim:

The ornamental design for a lawn umbrella, as shown and described.

ELIZABETH HARRISON HANNA.
